RIDING MOWER

James W. Zurek, Berkeley, Ill., assignor to International Harvester Company, Chicago, Ill., a corporation of New Jersey

Filed Jan. 15, 1965, Ser. No. 83,760

Term of patent 14 years

(Cl. D40—1)

FIG. 1.

FIG. 2.

FIG.3.

FIG.4.

FIG.5.

FIG. 6.

FIG. 7.

FIG. 8.

FIGURE 1 is a top plan view of a riding mower, showing my new design;

FIGURE 2 is a right side elevational view thereof;

FIGURE 3 is a left side elevational view thereof;

FIGURE 4 is a front elevational view thereof;

FIGURE 5 is a rear elevational view thereof;

FIGURE 6 is a top plan view of another embodiment of the riding mower of FIGURES 1 through 5;

FIGURE 7 is a side elevational view of the embodiment of the riding mower shown in FIGURE 6; and

FIGURE 8 is a front elevational view of the embodiment of the riding mower shown in FIGURES 6 and 7.

The rear portion of the modified embodiment disclosed in FIGURE 6 is substantially the same in appearance as the mower shown in FIGURE 5.

The dominant features of my design reside in the full line portions.

This is a continuation-in-part of design application Serial No. D. 79,657, filed April 22, 1964, and now abandoned.

I claim:

The ornamental design for a riding mower, substantially as shown and described.
